UNITED STATES PATENT OFFICE.

JOHN M. SPEER, OF FORT BRANCH, INDIANA.

FIREPLACE-HEATER.

1,228,254.

Specification of Letters Patent. Patented May 29, 1917.

Application filed June 8, 1916. Serial No. 101,585.

To all whom it may concern:

Be it known that I, JOHN M. SPEER, a citizen of the United States, residing at Fort Branch, in the county of Gibson and State 5 of Indiana, have invented new and useful Improvements in Fireplace-Heaters, of which the following is a specification.

The invention relates to a heater, and more particularly to the class of fire place 10 heaters or furnaces.

The primary object of the invention is the provision of a heater or furnace of this character wherein the same can be conveniently placed within the fire chamber of a fire place 15 for the purpose of conveying heat to a room or rooms, the heater or furnace being rendered more simple in construction and efficient in purpose than the ordinary furnace when located in a cellar or basement of a 20 house.

Another object of the invention is the provision of a heater or furnace of this character which is thoroughly reliable and efficacious in its purpose, strong, durable and 25 inexpensive in manufacture and installation.

Other objects will be in part obvious and in part hereinafter set forth.

The invention accordingly consists in the features of construction, combination of elements and arrangement of parts which will 30 be exemplified in the construction hereinafter described, and the scope of the application of which will be indicated in the appended claim.

35 In the accompanying drawings:

Figure 1 is a front elevation of a fire place showing the heater or furnace constructed in accordance with the invention installed;

Fig. 2 is a vertical transverse sectional 40 view thereof;

Fig. 3 is a vertical sectional elevation;

Fig. 4 is a sectional view taken approximately on the line 4—4 of Fig. 1;

Fig. 5 is a sectional view on the line 5—5 45 of Fig. 1.

Fig. 6 is a sectional view on the line 6—6 of Fig. 1.

Similar reference characters indicate corresponding parts throughout the several 50 views of the drawings.

Referring to the drawings in detail, A designates generally a fire place preferably formed from brick, and B the fire chamber therein, while C is the mantel wall of the ordinary well known construction. Arranged 55 within the fire chamber B is a heater body

10 preferably made from metal having a fire pot 11 in its lower portion and a grate 12, while below this fire pot is an ash pit 13 adapted to receive an ash pan 14 for the collection of ashes from the heater, although if preferred the bottom of the fire chamber B can be provided with a dump grate so that the ashes can be dropped into the cellar of a 60 house in the usual manner. Mounted upon 65 the front of the body 10 of the heater are the doors 15 and 16 respectively, the set of doors 15 when opened permitting access to be had to the interior of the body 10 of the heater so that coal can be poured into the fire box 70 11 thereof while the doors 16 when opened will give the proper draft to the heater for the combustion of the fuel therein.

Formed within the fire place A is a heat distributing chamber 17 which communicates with the chamber B through the open top of the latter and in the front of this fire place A at the bottom thereof are cold air inlets 18 for communication with the chamber 17, while near the top of the fire place 80 and leading from the chamber 17 are hot air outlets 19 which distribute the hot air to a room.

Leading from the body of the heater 10 is a smoke flue 20 which extends within a 85 chimney as usual.

Leading from the top of the chamber 17 and through the shelf portion of the mantel C is a hot air flue 21 which terminates at any suitable point for the distribution of 90 heat and this flue is provided with a regulating damper 22 of any approved type so that by the use of this flue 21 heat can be distributed into one or more rooms as may be desired.

95 The heat collected by the chamber 17 radiates through the body of the heater 10 and is distributed from the said chamber 17 through the outlets 19 into the room, as will be clearly apparent.

100 Arranged upon the body 10 of the heater is a hot water tank 23 from which leads a suitable discharge faucet 24 so that water can be drawn from the tank when required, the faucet being valved as usual, and the water may be introduced into the tank in any suitable manner. The heat from the body 10 of the heater will heat the water contained in the tank.

110 From the foregoing description, taken in connection with the accompanying drawings, the construction and operation of the

herein described fire place heater will be readily apparent and, therefore, a more extended explanation has been omitted.

Having thus described my invention, I 5 claim:

In combination, a fire place comprising back, side and top walls, the side walls being each formed with a vertical passage extending from the point adjacent the base of 10 the fire place upward, to a point above the fire place opening, a horizontal passage formed in the top wall and connecting with

each of the passages of the side walls, a heat collecting chamber located below and connecting with said horizontal passage, a heat 15 outlet above said chamber, damper controlled openings for said passages and a heater within the fire place.

In testimony whereof I affix my signature.

JOHN M. SPEER.
